UNITED STATES PATENT OFFICE.

HARRY G. WEYMOUTH, OF CLEVELAND, OHIO.

FUEL DEVICE FOR MOTORS.

Application filed August 1, 1921. Serial No. 489,044.

To all whom it may concern:

Be it known that I, HARRY G. WEYMOUTH, a citizen of the United States, and a resident of Cleveland, county of Cuyahoga, State of Ohio, have invented certain new and useful Improvements in Fuel Devices for Motors, of which the following is a specification.

This invention relates to internal combustion engines and more particularly to the fuel supplying means therefor.

One of the objects of the invention is to provide means for supplying relatively moist air to the intake manifold for the purpose of improving the quality of the fuel mixture and consequently deriving more power from a given amount of fuel and improving the economy of the engine.

Other objects and the features of novelty will be apparent from the following description taken in connection with the accompanying drawings, of which;

Figure 1 is a side elevation of an internal combustion engine embodying my invention, certain parts of an automobile being diagrammatically shown;

Fig. 2 is a horizontal section on the line 2-2 of Fig. 1;

Fig. 3 is a section on the line 3-3 of Fig. 2;

Fig. 4 is an enlarged fragment of the intake manifold and carburetor with my improved control valve therebetween; and

Fig. 5 is an enlargement of a fragment of Fig. 1.

Referring to the drawings, 10 indicates an internal combustion engine, 11 the intake manifold and 12 the radiator for cooling the cooling water of the engine. The carburetor is indicated at 13 and between the flange 14 on the carburetor and the flange 15 on the intake manifold I arrange the control valve 16 which consists of a rotatable ring 17 mounted in the valve body and provided with an elongated port 18 adapted to register with a port 19 extending through the side wall of the valve body. The ring valve 17 has secured thereto an operating arm 20 which projects through a slot 21 in the valve body and connects with one arm of a lever 22 which is mounted on the carburetor 13 and controls the throttle valve 23 by which the supply of fuel from the carburetor is regulated.

The valve body 16 is secured between the flanges 14 and 15 by means of bolts 24 and from Fig. 4 it will be noted that the valve port 18 is considerably elongated so that the communication between the port 19 and the intake manifold will be through a very much restricted passage during the early part of the opening movement of the throttle valve.

A valve body 25 is secured on the valve body 16 and has connected therewith a pipe 26 which extends into the upper part of the air space of radiator 12. The valve body 25 contains a valve 27 which consists simply of a cylindrical rod reduced to a semi-circular cross-section opposite the port 19 so that the latter may be closed from or put into communication with the pipe 26. The valve 27 is operated by a suitable rod 28 which extends to the dash 29 of the automobile so that the valve 26 may be controlled from the dash.

From the foregoing it will be evident that when the valve 27 is opened and the throttle valve 23 is closed the port 18 will be positioned approximately as indicated in Fig. 2 and no air will be supplied through the pipe 26. However, as the throttle valve 23 is opened by a rod 30 which connects with the lever 22 the restricted part of the port 18 will be carried into communication with the port 19 and permit a small amount of air to be drawn into the intake manifold from the pipe 26. As the throttle valve 23 is further opened the wider part of the port 18 will be gradually brought into registration with the port 19 and finally when the throttle valve is fully opened the port 19 will be in full communication with the intake manifold and air will be drawn in through the pipe 26.

Since the pipe 26 communicates with the air space of the radiator, the air withdrawn therefrom must be replaced and this is supplied by the usual overflow pipe 31 and for the purpose of insuring the maximum amount of moisture in the air that is conveyed to the intake manifold, I have provided a return bend or goose-neck 32 on the upper end of the pipe 31 so that the air drawn into the radiator will be delivered under the surface of the water in the radiator, as clearly indicated in Fig. 5, the air in this case being delivered from the outlet

33 at the end of the pipe 32 and bubbling up through the water into the air space of the radiator.

In order to prevent the overflow pipe 31 from siphoning off that part of the radiator water that is above the outlet 33, whenever the radiator is filled above the return bend 32 and the motor is not operating, I have provided a small vent opening or pin-hole 10 34 at the top of the return bend 32. The opening 34, being very small, will break the vacuum in the return bend, when the motor is not operating, and thus prevent the water from being siphoned off. The size of 15 the opening 34 being very small, as compared with the outlet 33, the amount of air that will be admitted to the radiator through the opening 34, when the motor is operating, will be relatively insignificant so that the vacuum produced in the radiator, 20 above the surface of the water, will cause the air to be drawn in through the pipe 31 and discharged through the outlet 33 into the water, as previously described.

I am aware that various devices for supplying auxiliary air to an intake manifold have been heretofore suggested and that it has also been suggested that the air be taken 25 from the radiator but I am not aware that it has been heretofore proposed to automatically control the supply of auxiliary air, by and in accordance with the throttle valve. Moreover, I am not aware that means have 30 been heretofore provided for insuring a plentiful supply of moisture in the air by causing the air to be delivered under the surface of the water in the radiator.

Devices heretofore suggested for supplying auxiliary air to the intake manifold, 35 have been controlled manually from the dash of the vehicle with the result that too much air is supplied under conditions where it is desirable to have a very rich mixture, so that in many cases these auxiliary air 40 supplying devices have been more of a hindrance than a help and they have necessitated constant manual control by the op-

erator of the vehicle which takes his attention from the other control operations necessary to operate a vehicle.

With my device, however, the control of the auxiliary air supply is automatic and graduated in accordance with the control of the throttle valve so that it requires little or no attention from the operator of the 55 vehicle.

Having thus described my invention what I claim is:

1. The combination of a motor vehicle radiator, an internal combustion engine, an intake conduit for said engine, a throttle valve for said intake conduit, controlling means for said valve, said radiator having an open overflow pipe connected with the upper part thereof provided with a return bend at the top so that air supplied therethrough will be delivered into the water in the radiator, a conduit independent of said overflow pipe extending from the space in said radiator, above the water level, to said intake conduit for supplying moist air to the latter, and a valve for controlling said second-mentioned conduit operatively connected with said throttle valve so as to be automatically controlled thereby.

2. The combination of an internal combustion engine, an intake conduit therefor, a valve body attached to said conduit and forming an extension thereof, means for supplying a combustible mixture through said valve body, a radiator, a conduit for conducting moist air from the upper part of said radiator to said valve body, and an overflow pipe for said radiator having a return bend at the upper end thereof projecting below the surface of the water in the radiator whereby air supplied through said pipe will be delivered in the water, said return bend having a vent opening at the top to prevent siphoning off the water of the radiator.

In testimony whereof I affix my signature.

HARRY G. WEYMOUTH.
